UNITED STATES PATENT OFFICE.

REUBEN B. BENJAMIN, OF CHICAGO, AND CHESTER E. WARNER, OF BERWYN, ILLINOIS, ASSIGNORS TO BENJAMIN ELECTRIC MANUFACTURING COMPANY, OF CHICAGO, ILLINOIS, A CORPORATION OF ILLINOIS.

ELECTRICAL CONNECTER DEVICE.

Application filed May 10, 1920. Serial No. 380,378.

To all whom it may concern:

Be it known that we, REUBEN B. BENJAMIN, a citizen of the United States, residing at Chicago, in the county of Cook and State of Illinois, and CHESTER E. WARNER, a citizen of the United States, residing at Berwyn, in the county of Cook and State of Illinois, have invented certain new and useful Improvements in Electrical Connector Devices, of which the following is a full, clear, concise, and exact description, reference being had to the accompanying drawings, forming a part of this specification.

Our invention relates to electrical connector devices, and more specifically that type of electrical connector device known as plug clusters.

One of the objects of our invention is to provide an improved electrical connector device which will be durable and efficient in use, simple in construction and cheap to manufacture.

Further objects will appear from the detailed description to follow and from the appended claims.

In the drawings in which two embodiments of our invention are shown:

Fig. 1 is a side elevation of a plug cluster;

Fig. 2 is an axial section of the plug cluster shown in Fig. 1;

Fig. 3 is a plan view of the receptacle portion of the plug cluster;

Fig. 4 is a side elevational view of the plug cluster, part being broken away to show the interior construction;

Fig. 5 is a bottom plan view of part of the device;

Fig. 6 is a horizontal section substantially on the line 6—6 of Fig. 2;

Fig. 7 is a perspective view of part of the switch mechanism;

Fig. 8 is a vertical section substantially on the line 8—8 of Fig. 3;

Fig. 9 is a vertical section substantially on the line 9—9 of Fig. 3;

Fig. 10 is a plan view of part of a receptacle, showing another embodiment of our invention;

Fig. 11 is a side elevational view of the plural receptacles shown in Fig. 10, part being broken away; and

Fig. 12 is a perspective view of a detail.

In order to give a general idea of the construction shown, and referring first to the

form shown in Figs. 1 to 9 inclusive, the 55 construction here shown is an electrical connector device, having a plug portion for screwing into an Edison socket, two receptacle portions of the Edison type, and two 60 switch mechanisms, one for each of the two 65 receptacle portions for controlling the circuit from the plug portion to these receptacle portions respectively. The plug portion of the device is of the swivel shell contact type, that is, the threaded shell contact is swiveled on the device, so that it can be screwed into the socket without rotating the receptacle part of the device, and so that after the screw-shell contact is screwed into the socket the receptacle portion can be 70 turned to any desired position to bring the pull chains of the switch mechanism to the desired location. Both of the threaded shell contacts of the receptacle portion are permanently electrically connected with the 75 threaded shell contact of the plug portion, the two switch mechanisms being interposed between the center contact of the plug portion and the two center contact of the receptacle portion respectively. 80

Referring now to the drawings in detail, the plug portion of the device comprises a substantially cylindrical insulating base 10, a center contact member 11, supported by the insulating base 10, and a threaded shell contact member 12 surrounding the insulating base 10 and swiveled with respect thereto, whereby the contact 12 can be screwed into an Edison socket without rotating the insulating base 10. 85

The receptacle portion of the device comprises a one-piece insulating base 13, a pair of Edison sockets 14 and 15, extending at an angle with respect to each other, and a pair of switch mechanisms 16 and 17 located in 95 recesses in the insulating base 13, and controlling the circuit between the center contact 11 of the plug and the center contact 18 and 19 respectively of the receptacles 14 and 15. 100

The insulating base 13 and the parts directly supported thereby are supported from the plug portion by means of a yoke-shaped metal stamping 20, and a pair of screws 21 and 22, which parts 20 and 21 also serve to electrically connect the threaded shell receptacle contacts 14 and 15 with the threaded shell plug contact 12. (See particu- 105

larly Fig. 2.) In order to afford an electrical connection between the yoke member and the plug threaded shell contact 12, a sheet metal conducting member 23 is secured 5 to the lower end of the plug, this member having an outwardly extending flange 24 which engages an annular shoulder at the lower end of the threaded shell contact 12, said member 23 having an inwardly extending 10 annular flange 25, against which the annular portion 26 (Fig. 6) of the yoke member 20 is clamped.

This yoke 20 is clamped in place by means of a tubular eyelet member 27 (the upper 15 portion of which forms the center contact 11 of the plug) and the lower portion of which is riveted as indicated at 28, to hold the yoke 20 in place. A washer 29 is provided to form an extended bearing for the rivet, 20 and an insulating disc 30 is interposed between the washer 29 and the annular portion 26 of the yoke 20 for insulating the washer from the yoke. The threaded shell contacts 14 and 15 are electrically connected 25 with the screws 21 and 22 respectively, by means of integral ears 31 and 32 respectively, having openings through which the screws 21 and 22 extend, these screws having 30 their upper ends threaded into the yoke 20.

The switch mechanism for controlling the circuit from the plug center contact 11 to the receptacle center contacts 18 and 19 will now be described. These two switch mechanism 35 16 and 17 are similar in construction, and a description of one will suffice for both. A common support is provided for the two switch shafts, this common support being shown in perspective in Fig. 7. This 40 shaft support also forms part of the electrical connection from the center contact 11 to the two switch mechanisms. It comprises a sheet metal stamping having a threaded shank 33, by means of which it is secured to the insulating base 13, and two oppositely stamped-up bearing portions 34 and 35 respectively, forming bearings for the switch shafts 36 and 37 respectively of the switch mechanisms 16 and 17 respectively. It is electrically connected with the center contact 11 by means of a pair of channel-shaped spring tongues 38 which have a telescopic engagement with the tubular member 27. The two switch shafts 50 36 and 37 are thus electrically connected with the center contact 11. For securing the stamping in place, the shank 33 is inserted through an opening in the insulating base, and a nut 33^a is threaded on to the end of the shank.

Each of the switch mechanisms 16 and 17 comprises in addition to the switch shafts 36 and 37 a spring contact member 39 (Fig. 8) a commutator 39^a for making and breaking 65 the circuit between the contact 39 and

the switch shafts 36 and 37, and mechanism 40 for imparting a step-by-step movement to the commutator 39^a. The commutator 39^a comprises an insulating brush-carrier 41, and a semi-circular brush or contact 42, eccentrically secured on the brush-carrier 41. This contact or brush 42 is always electrically connected with the switch shaft (36 or 37) by means of an integral inwardly-extending arm 43 (Fig. 3). The brush or contact 42 is alternately moved into and out of contact with respect to the spring contact member 39 by means of the ratchet mechanism 40. This step-by-step ratchet mechanism 40 comprises a pull chain 44, a chain rail 45, to which the pull chain 44 is secured, and a coil torsion spring 46 for returning the pull chain 44 after it has been pulled down manually. Each downward pull of the chain 44 moves the brush-carrier 39^a half a revolution. When the pull chain is released, the spring 46 returns the chain rail and chain, the brush carrier 39^a, however, remaining stationary during this return movement. The brush-carrier is prevented from returning with the chain rail by means of the spring contact member 39, which snaps off from the shoulder 47 or the shoulder 48, when the chain 44 is pulled, and engages behind one of these shoulders to prevent a return movement of the brush-carrier.

The spring contact 38 alternately snaps off from the brush 42 onto the insulating brush-carrier 39^a and from the insulating brush-carrier 39^a into engagement with the brush 42. The spring contact member is so constructed that a substantially simultaneous double break is effected in the circuit, this being accomplished by providing two spring tongues 49 and 50 respectively, the spring tongue 49 cooperating with the brush 42, and the spring tongue 50 cooperating with a contact portion 51, which is struck up from the stamping 52, which secures the contact member 39 in position. The tension in the contact member 39 is such that as the spring contact finger 49 snaps off behind the shoulder 48, the spring contact finger 50 will simultaneously be jerked away from the contact member 51, so that there will be a break both between the contact 42 and the spring contact finger 49, and between the spring contact finger and the contact member 51. The base portion 53 of the member 39 is held under the spring securing member 52 but is insulated therefrom by means of an insulating strip 54, so that no current flows between this base portion 53 of the spring contact member and the securing member 52. The securing member 52 is held in place to secure the spring contact by means of a screw 55 (see particularly Figs. 5 and 9) which also serves to electrically connect the contact member 51 with the center contact (18 or 19). Each

of the center contacts 18 and 19 are formed as a part of a sheet metal stamping, having an ear-portion 56 through which the screw 55 extends, and a strap portion 57 connecting the ear-portion 56 with the center contact proper.

A spherical sheet-metal housing is provided for the receptacle portion of the device, this housing comprising a lower hemispherical portion 58, permanently secured to the insulating base 13, and an upper hemispherical portion 59 detachably secured to the lower hemispherical portion 58. A pair of tubular sheet-metal sleeves 60 are provided for housing the threaded shell receptacle contacts 14 and 15 respectively, these sleeves being insulated from the threaded shell contact by means of fibre cups or sleeves 61. The outside sheet-metal sleeves 60 are secured to the hemispherical housing member 58 by means of an outside annular bead 62, and an inside annular flange 63.

The threaded shell contact of the plug is provided with an annular insulating thumb piece 64 for use in screwing the shell into the socket and with an insulating collar 65 to insulate the outer end of the shell contact 12. The lower hemispherical housing 58 is secured in place on the insulating base 13 by having its upper edge flanged over an annular shoulder 66 on the insulating base 13 as indicated at 67. The upper hemispherical portion 59 has a skirt portion 68 which fits down over the upper edge of the lower hemispherical portion 58.

It will be noted that the lower portion of the plug cluster including the insulating base 13, the spherical casing, the receptacle contacts and the switch mechanism can be readily disconnected from the plug portion of the plug cluster simply by unscrewing the screws 21 and 22. The hemispherical portion 59 can come off along with the insulating base 13, as it has a pair of notches 69 in its upper edge, which permit it to slip past the lugs 70 of the yoke 20. After the insulating base 13 and the parts carried thereby have been thus disconnected from the plug portion, the hemispherical portion 59 of the cover can be easily slipped off from the insulating base 13, thus giving access to the switch mechanisms 16 and 17 for inspection or for any desired purpose.

The circuit has been outlined in connection with the description of the construction, and is from the center contact 11 through the tubular member 27, the channel-shaped contact fingers 38, bearing portion 34 or 35, switch shaft 36 or 37, contact member or brush 42, spring contact members 39, contact member 51, screw 55, center contacts 18 and 19, through whatever translating device may be inserted in the socket to shell contacts 14 and 15, screw 21 or 22,

yoke member 20 and conducting member 23 to the threaded shell contact 12 of the plug.

The plug cluster may be connected up with an Edison socket by taking hold of the spherical casing and holding it in one hand, and screwing the threaded shell contact 12 into the socket with the other hand.

The switch mechanism is alternately moved to "on" or "off" position by pulling down on the chain 44, to control the circuit between the center contact 11 of the plug and the center contacts 18 and 19 of the receptacles.

In the form of my invention shown in Figs. 10, 11 and 12, the construction is substantially the same as in the form previously described, except that instead of having means for screwing into an Edison socket, means are provided for securing the device to a threaded nipple and wiring terminals are provided for the feed wires.

The switch mechanism is substantially the same as in the form previously described, except that in this form the shaft bearing member 71 (see Fig. 12) instead of having a spring contact member at its upper end, is provided with a bracket 72 terminating in a binding plate 73, into which the binding screw 74 is threaded, the binding plate 73 having a plurality of fingers 75 terminating in upwardly extending lugs 76 for holding the wire in position underneath the head of the binding screw. Also in this form the screws 21 and 22 which engage the threaded shell receptacle contact, instead of being threaded into a yoke member 20, are threaded into a yoke member 78, which yoke member is provided with a binding screw 79, whereby one of the feed wires may be secured to it.

The upper hemispherical portion 80 of the casing is detachably connected with the lower hemispherical portion 81 by means of an inwardly extending projection 82, which engages a registering opening in a flexible portion 83 of the lower hemispherical portion 81, so that by pressing inwardly on the flexible portion 83 the projection 82 will be disengaged from the registering opening, to permit the parts to be separated. A suitable engagement may be provided on the side opposite the projection 82, which will be constructed so that releasing the projection 82 will permit the disengagement of the opposite side of the hemispherical casing portions 80 and 81.

In wiring the device, the upper hemispherical casing portion 80 is removed, the feed wires are led down through the opening in the bushing 84, and secured underneath the binding screws 74 and 79 respectively, the bushing 84 is then screwed into place on the nipple through which the feed wires are led, and the lower hemispherical

portion 81 of the casing is secured to the upper hemispherical portion 80.

The circuit from the member 71 to the yoke member 78 is substantially the same as the circuit from the switch member to the yoke member 20 in the form shown in Figs. 1 to 9 inclusive.

Having thus described our invention, what we claim as new and desire to secure by Letters Patent, is:

1. A plural switch receptacle comprising two receptacles and two switch mechanisms for controlling the circuit to said receptacles respectively, said switch mechanisms comprising a pair of switch shafts, one for each receptacle, and an integral bearing member having a bearing for each of said switch shafts.

2. A plural switch receptacle comprising two receptacles, and two switch mechanisms for controlling the circuit to said receptacles respectively, said switch mechanisms comprising two switch shafts and an integral metal bearing member having two bearing portions, one for each switch shaft, said bearing member and switch shafts forming part of the electrical circuit.

3. A plug receptacle comprising a plug portion having a tubular member of conducting material extending therethrough, said receptacle portion having a switch mechanism comprising a switch shaft and a sheet metal stamping provided with a bearing portion for said switch shaft, said bearing portion having a contact tongue secured thereto and extending up into said tubular member.

4. A plural switch receptacle comprising

two receptacles and two switch mechanisms for controlling the circuit to said receptacles respectively, said switch mechanisms comprising a pair of switch shafts, one for each receptacle, and an integral bearing member having a bearing for each of said switch shafts, said bearing member being of sheet material, and said bearing portions being struck up therefrom and lying in different parallel planes offset with respect to each other.

5. A plural switch receptacle comprising two receptacles and two switch mechanisms for controlling the circuit to said receptacles respectively, said switch mechanisms comprising a pair of switch shafts, one for each receptacle, and an integral bearing member having a bearing for each of said switch shafts, said bearing member having a shank portion by which it is secured to said receptacle portion.

6. A plug receptacle comprising a plug portion and a receptacle portion, said plug portion having a center contact and shell contact swiveled with respect to said center contact, and said receptacle portion comprising two receptacles, each having a center contact and a shell contact, and means for use in mechanically connecting said receptacle portion to said plug portion comprising a metal member electrically connected with said plug shell contact and with said receptacle shell contact.

In witness whereof, we have hereunto subscribed our names.

REUBEN B. BENJAMIN.
CHESTER E. WARNER.
